TELEGRAPH TYPEWRITER PASTING PLATFORM

Application filed January 6, 1932. Serial No. 584,976.

This invention relates to a method of and apparatus for facilitating the handling of the message tape which issues from a telegraph typewriter machine of the sort adapted for both transmission and reception of messages, and has for its object to reduce the space requirements necessary for such a machine and also to make the application of the printed tape to a message sheet more convenient and rapid.

With such machines the customary practice is to have the operator moisten and apply the message tape to a sheet located at the side of the machine where the tape issues. This requires substantial space at the side of the machine and also involves either the operator stretching or shifting his position in order to change from transmission to message reception. In brokerage offices and the like where rentals are high and space is at a premium this practice is objectionable, not only because of the excessive space requirements but also because of the time and inconvenience of the operator in either moving or stretching in order to change from receiving to transmitting.

One solution of the problem has contemplated the provision of a platform pivoted to the front of the machine casing and adapted to serve as a work-holding and message pad supporting or gumming platform located over the machine keyboard.

This suggestion also contemplated this platform being raised out of the way during message transmission when it is adapted to serve as a copy holder. There are several objections to this suggestion among which may be mentioned that since the cover of these machines is generally loose and not tightly fitted in place, an unsteady support is provided for the message reception sheet during the pasting or gumming operation. Also when this platform is located over the keyboard it has been customary to locate the moistening device on the side of the machine, with the result that the operator has to draw a piece of message tape over the moistener in a general front and back motion which requires considerable stretching and inconvenience.

According to this invention these disadvantages are eliminated. The tape moistening operation may be performed by moving the tape across the front of the machine with the moistener being located at one side of the keyboard and the gumming or message pad platform is located so as to be at a convenient height below and in front of the keyboard yet not in the way of the easy moistening operation.

Specifically a shallow supporting member is provided for the telegraph typewriter machine and the message pad holding platform is slidable from beneath the machine keyboard forwardly for message reception. The platform is so constructed as to be readily and securely clamped to the shallow supporting member so that a satisfactory and steady support is provided during the wiping and pasting operations.

In order to change from receiving to transmitting the operator merely moves the platform inwardly below the machine keyboard, a substantial knock or thrust being necessary to unclamp the platform.

Referring to the drawing:

Fig. 1 is a perspective view of an embodiment of this invention with the message pad platform in extended position.

Fig. 2 is a transverse section through the machine supporting member of Fig. 1 with the platform in its inoperative position for transmission of messages on the machine.

Fig. 3 is a view corresponding to Fig. 2 but with the platform in extended position. Fig. 4 is a partial section on the line 4-4 of Fig. 2.

A customary form of telegraph typewriter machine is shown at 10 and is of the type adapted for both message transmission and message reception, the received message being printed by the machine on a gummed tape 11 issuing from the left side of the machine as shown. The machine 10 is provided with the usual keyboard 12 at the front and the casing of the machine may or may not be provided with a transparent window through which the printing mechanism may be seen. Secured to the side of the support 16 and extending above the keys is a wick or moistening device 13 of customary form. After

tearing off the message tape it is passed across the moistening device 13 by moving the tape in a lateral direction across the front of the machine above the keyboard.

5 The operator then proceeds to apply the moistened gummed tape to the message sheet or pad 14, held on the platform 15 as illustrated. A spring clip 19 of the shape shown provides a convenient clipping means for the 10 message pad.

A shallow supporting member 16 is mounted beneath the machine and is of such height that the machine is not unduly raised, in fact the height of said supporting member 16 is 15 generally between two and three inches.

As shown in Figs. 2 and 3 the platform 15 is slidable within the supporting member 16 somewhat after the manner of a well fitted desk slide or drawer except that a simple and 20 automatic clamping mechanism is provided for holding the platform in extended position. The clamping means comprises a wedge 17 on the rear portion of the platform 15 which cooperates with a wedge 18 25 secured to the supporting member 16. These wedges and the entire construction may be of either wood or metal, wood being most frequently used because of the simplicity of the construction and economy in production 30 cost.

For message reception the platform 15 is pulled out by grasping the knob 20 on the front of the platform in much the same manner as an ordinary drawer is pulled out. As 35 the platform reaches the limit of its extended position the wedges 17 and 18 engage and preferably the platform is drawn out with enough force to make the wedges provide a clamping action for the platform so that the 40 platform is clamped to the supporting member 16.

Since the supporting member 16 is generally mounted at the front edge of a desk, table or counter it will be understood that 45 when the platform is extended, such platform together with the supporting member 16 constitute a lever. The overhanging lever portion of platform 15 when in extended position is counterbalanced by the weight of the 50 machine 10 acting on the rear portion of the supporting member 16 or lever so that the weight of the machine assists in providing a steady and satisfactory support for the message pad 14, and any downward thrusts 55 or pressure on the platform and pad during the pasting and wiping operations of affixing the tape to the message sheet will not cause any wobble or movement of the platform.

Among the advantages of this invention 60 may be mentioned the increased convenience and minimum space requirements for manipulating the message tape. The location of the moistening device 13 at the side of the keyboard and in front of the machine permits the operator to moisten the tape by a

movement of the tape across the front of the machine without having to stretch himself as would be necessary if the tape were to be moistened by moving it in a front or backward motion. Locating the message platform below and in front of the keyboard does not impede free movement of the tape during the moistening operation and yet provides a satisfactory support for the message pad close to the keyboard where the pasting may be 75 done most rapidly and conveniently.

If desired a moistening device of the type indicated by the numeral 16 in the patent of Blanchard, et al., 1,831,700, dated November 10, 1931, may be used and held in the operator's right hand, but experience has shown that this type of moistener is not adapted for the most rapid work such as is necessary in brokerage offices because such a moistener requires the delay incident to threading the 80 message tape into it. The operator may or may not use a thimble of the sort illustrated by the numeral 18 in said Blanchard patent, to assist in pasting and wiping and tearing off the tape where needed as it is being applied to the message sheet.

It will be noted that the message pad 14 is held by the spring clip 19 in such position that the platform may be moved inwardly and the pad retained in position without being 95 removed from the platform.

When it is desired to stop receiving on this machine and begin transmitting messages, the change may be quickly effected by giving the outer edge of the platform 15 an inward 100 knock or thrust sufficient to release the clamping wedges. Such release of the platform clamping means and its movement out of the way to a position beneath the machine keyboard may thus be effected in a single 105 movement by one hand of the operator. When the platform is telescoped within the supporting member 16 it is entirely out of the way of the operator allowing free movement to the operator's hands and forearms during manipulation of the keys for message 110 transmission.

One advantage of locating the platform below and in front of the machine keyboard during message reception is that the space 115 above the keyboard is left clear to permit the convenient and unimpeded tape moistening movements. Another advantage of locating the pad platform in such position is that it may be steadied and made firm not only by 120 the wedge clamping means but also by the weight of the machine holding down the supporting member 16 and acting as a counterbalancing means for the platform or overhanging lever portion 15. When no space 125 on the work-table or counter 21 is required at the side of the machine for the pasting portion, it will be appreciated that with the present invention these telegraph typewriter machines may be placed close together, leav- 130

ing only room enough for the machines and operators. Still further space economy may be attained by having the machines arranged at an angle to the front edge of the work-table, in which latter case this front edge of the work-table may or may not be recessed to provide space for the operator. The front portion of the work-table 21 serves as a fulcrum for the lever constituted by the extended platform 15 and the supporting member 16 so that the weight of the machine 10 may constitute a counterbalancing means for any downward thrust on the overhanging platform 15.

15 As used in the appended claims the term "clamping means" does not contemplate any special degree of pressure. An important consideration is that the pasting platform 15 shall be firmly held in operative position 20 without the usual looseness found in desk slides and the like, but yet be capable of easy movement into and out of its operative and inoperative positions.

We claim:

25 1. The combination with a tape printing telegraph typewriter machine adapted for both message transmission and reception, of a movable platform adapted for supporting a message reception sheet to which the tape 30 may be pasted in front of and below the machine keyboard, said platform forming part of a lever, and lever counterbalancing means for downward pressure on the platform, said counterbalancing means comprising said machine, said platform being slideable within the portion of said lever under said machine, and means for clamping said platform to said lever portion when said platform is in its extended position, said 35 last mentioned means being effective only in fully extended position of the platform.

2. The combination with a tape printing telegraph typewriter machine adapted for both message transmission and reception, of a movable platform adapted for supporting a message reception sheet to which the tape 45 may be pasted in front of and below the machine keyboard, said platform forming part of a lever, and lever counterbalancing means for downward pressure on the platform, said counterbalancing means comprising said machine, said platform being slideable within the portion of said lever under said machine, and means for clamping said 50 platform to said lever portion when said platform is in its extended position, said clamping means being releasable by an inwardly directed thrust upon said platform.

60 3. A supporting member for a tape printing telegraph typewriter machine, a message pad holding platform slideable from within said supporting member to an extended position in front of the machine, and means for 65 automatically and rigidly clamping said

platform in its extended position in response to pulling the same outward.

4. The combination with a tape printing telegraph typewriter machine adapted for both message transmission and reception, of a movable platform adapted for supporting a message reception sheet to which the tape may be pasted in front of and below the machine keyboard, said platform forming part of a lever, and lever counterbalancing means for downward pressure on the platform, said counterbalancing means comprising said machine, said platform being slideable within the portion of said lever under said machine, and means for clamping said platform to said lever portion when said platform is in its extended position, said clamping means comprising cooperative wedging portions on said platform and on said lever portion below said machine.

5. A shallow supporting member for a tape printing telegraph typewriter machine, a message pad holding platform slideable from within said supporting member to an extended position in front of the machine, and cooperative wedges, one secured to said platform and another secured to said supporting member for clamping said platform when in extended position substantially rigidly to said supporting member.

6. The combination with a tape printing telegraph typewriter machine having a keyboard and adapted for both the transmission and reception of messages, of a message blank supporting means on which the tape may be pasted, said means being slideable in and out beneath the keyboard of said machine and means for automatically clamping said slideable means in extended position in response to the outward movement thereof, said clamping means being released in response to an inward thrust for moving said slideable means inwardly beneath the machine keyboard whereby said machine and the supporting means may be quickly conditioned for message transmission or reception.

7. The combination with a tape printing telegraph typewriter machine having a keyboard and adapted for both the transmission and reception of messages, of a message blank supporting means on which the tape may be pasted, said means being slideable in and out beneath the keyboard of said machine, and tape moistening means fixedly secured adjacent the machine keyboard at such a height and forward position as to enable the operator to pass the tape simultaneously across the moistening means and keyboard in conditioning the tape for pasting to a message blank on said supporting means, whereby the operator may moisten and paste the tape with the expenditure of little time and effort.

8. The combination with a tape printing telegraph typewriter machine having a keyboard and adapted for both the transmission

and reception of messages, of a message blank supporting means on which the tape may be pasted, said means being slidable in and out from beneath the keyboard of the machine,
5 and tape moistening means adjacent the machine keyboard at such height and forward position as to enable the operator to pass the tape simultaneously across the moistening means and in front of the machine in conditioning the tape for pasting to a message blank on said supporting means whereby the operator may moisten and paste the tape with the expenditure of little time and effort.

10 9. The combination with a tape printing telegraph typewriter machine adapted for both message transmission and reception, of a movable platform adapted for supporting a message reception sheet to which the tape may be pasted, in front of and no higher than
15 the machine keyboard, and means for quickly clamping said plate firmly in operative position, said clamping means being quickly releasable by a single movement of the operator's hand to enable the plate to be moved
20 to an out-of-the-way position beneath the machine and in rear of its operative position.

Signed at New York, in the county of New York and State of New York, this 29 day of December, 1931.
